(57) **CLAIM**

The ornamental design for a utility shoulder belt, as shown and described.

DESCRIPTION

FIG. 1 is a front perspective view of a utility shoulder belt with a pocket assembly in accordance with the invention.

FIG. 2 is a right side elevational view in accordance with the invention.

FIG. 3 is a rear elevational view in accordance with the invention.

FIG. 4 is a front elevational view in accordance with the invention.

FIG. 5 is a left side elevational view in accordance with the invention.

FIG. 6 is a bottom plan view in accordance with the invention.

FIG. 7 is a top plan view in accordance with the invention.

FIG. 8 is a front perspective view of the pocket assembly in accordance with the invention.

FIG. 9 is a top plan view of the pocket assembly in accordance with the invention.

FIG. 10 is a front elevational view of the pocket assembly in accordance with the invention.

FIG. 11 is a bottom plan view of the pocket assembly in accordance with the invention.

FIG. 12 is a rear elevational view of the pocket assembly in accordance with the invention.

FIG. 13 is a right side elevational view of the pocket assembly in accordance with the invention; and,

FIG. 14 is a left side elevational view of the pocket assembly in accordance with the invention.

The pocket assembly is not shown in FIGS. 2-7 for convenience of illustration.

The broken lines in FIG. 1 represent environment that forms no part of the claim.
